VALVE

Henry P. Birkemeier, Chicago, Ill.

Application July 22, 1944, Serial No. 546,101

5 Claims. (Cl. 236—59)

1

My invention relates to valves and more particularly to a valve incorporating a self-draining feature which enables the associated structure, such as a radiator, to be automatically drained under selected conditions.

For the purpose of description, my improved valve will be described as of the radiator type for use in a steam heating system. When the standard radiator valve is closed with steam in the line, the steam condenses in the radiator with consequent danger of freezing if the steam should be shut off for an indefinite period, such as in public buildings, schools, etc., over weekends or holidays. Thermostatically controlled valves have heretofore been devised to automatically drain the condensate back to the boiler, but so far as I am aware, such valves have been relatively complicated in construction and have involved either a special type of valve, or an auxiliary construction for use with a standard radiator valve which was structurally independent thereof.

It is therefore the principal object of my invention to devise a valve which is characterized by standard features in respect of the valve body, the valving element and the operating stem and handle therefor, but in which the element is slightly modified and associated with a thermostatic control which provides for drainage of the associated part when the element is in a closed position.

A further object is to provide a valve of the character indicated in which the modification of the valving element may be quickly and easily effected without removing the valve body from the steam line.

These and further objects of the invention will be set forth in the following specification, reference being had to the accompanying drawing, and the novel means by which said objects are effectuated will be definitely pointed out in the claims.

In the drawing:

Fig. 1 is an elevation, partly in section, of a portion of a steam radiator and my improved valve connected in the steam line leading thereto.

Fig. 2 is a section along the line 2—2 in Fig. 1.

Fig. 3 is a fragmentary section showing a modified arrangement of the valve.

Referring to the drawing, the numeral 10 designates a steam pipe whose delivery end is threaded in the inlet side of a valve 11 having a body 12 of the angle and globe type. The delivery side of the body 12 is connected by a nipple 13 to a radiator 14. Interiorly of the body is a valve seat 15 that is engaged by a valve head 16 that may be advanced or retracted by a threaded stem 17 when actuated by the grip 18 in the usual manner. So far as described, the valve 11 is of standard construction, but is characterized by the objections already noted.

To condition the valve for automatic drain-

2

age of the radiator when the valve is closed, a plurality of radial passages 19 are formed in the head 16 in such a position that they are disposed well above the seat 15 when engaged by the head 16. As indicated in Fig. 1, the passages 19 extend inwardly from the periphery of the head for a limited distance only and each passage at its inner end connects with a passage 20 that is parallel with the axis of and extends to the underside of the head 16. Accordingly, when the head engages the seat 15, communication is established between the pipe 10 and the interior of the valve body 12 above the seat.

It is necessary to control the flow of steam through the passages 19 and 20, because otherwise steam would flow to the radiator when the valve 11 was closed. This result is accomplished by means of an annular valve plate 21 which is slidable vertically on a stem 22 that depends axially from the head 16, the plate being capable of closing the lower ends of the passages 20. The plate 21 is controlled by a thermostatic element 23 which may be composed of a pair of bimetallic strips 24 and 25, each of which is horizontally U-shaped. The upper end of the strip 24 is secured to the under side of the plate 21 while the lower end of the strip 25 is attached to an adjusting nut 26 threaded on the stem 22, and the other ends of the strips 24 and 25 are secured together and are guidable along the stem. A lock nut 27 maintains the adjusted position of the nut 26. The element 23 is arranged to move the plate 21 to close the passages 20 when subjected to heat, as during the presence of steam in the line, and to retract the plate to an open position when cold. The shape of the thermostatic element 23 is a matter of choice since the broad aspects of the invention contemplate the carriage of a thermostatically controlled valve by the valve head of a standard valve.

When the valve head 16 is in the raised or open position, the valve 11 functions in the normal manner to pass steam to the radiator 14. At this time, the thermostatic element 23, being subjected to heat, has shifted the plate 21 to close the passages 20, and the steam pressure acting on the plate serves as an additional closing factor.

When the valve 11 is closed, the steam pipe 10 cools down and the element 23 retracts the plate 21 to uncover the passages 20 and thereby provides a communicating path between the interior of the valve body 12 and the pipe 10. Therefore, as the steam condenses in the radiator 14, the water may freely return to the boiler. Freezing of the water in the radiator is accordingly prevented, as well as any tendency to a water hammer effect when the valve 11 is again opened. It is also impossible to fill the radiator with water until it leaks out of the radiator air vents.

A frequent cause of water in one-pipe steam

radiators is the fact that the ordinary radiator valve may not be closed tightly when heat is no longer desired. However, steam is still present in the supply pipe and will leak through the valve and condense in the radiator. The imperfect seating of the valve may be insufficient to drain this condensate back to the boiler when the steam pressure in the pipe falls. My improved valve would drain this condensate adequately and promptly.

In Fig. 3 is illustrated a modified valve construction wherein a valve head 28 is provided with connecting radial and longitudinal passages 29 and 30, respectively, all corresponding to the comparable parts shown in Fig. 1, and the passages, as before, providing communication between the interior of the valve body 12 and the steam pipe 10. A valve plate 31 controls flow through the passages 29 and 30 and is slidably in a stem 32 that is threaded in and depends from the valve head 28. The under side of the plate 31 is contacted by one end of a thermostatic element 33 which may be constructed similarly to the element 23 and is guided in its movements by the stem 32. The other end of the element 33 bears against an adjusting nut 34 threaded on the stem 32 which is held in adjusted position by a lock nut 35. So far as described, the foregoing construction is identical with that shown in Fig. 1, but differs therefrom in that the element 33 is not secured to the valve plate 31 and adjusting nut 34 so that the element is capable of movement relative to the plate. A further distinction consists in the provision of springs 36 in the passages 30 which tend to shift the plate 31 to an open position when not restrained by the element 33 or pressure in the supply pipe.

The operation of the modification is generally identical with the arrangement illustrated in Fig. 1, except that, in the former, the capacity of the plate 31 for independent movement enables this plate to maintain the closure of the passages 30 so long as adequate pressure exists in the pipe 10, even though the temperature may have dropped sufficiently to cause a retraction of the element 33. Moreover, in the modification, both heat and pressure act independently to hold the plate 31 closed.

My improved valve may also be employed in hot water heating systems since it would enable water to drain from any closed radiators when the system is drained which is of particular advantage in large installations. The invention is not restricted to use with steam and hot water heating systems, but also may be used under any conditions requiring a self-draining valve where heat is available. Moreover, the valve may be used in any position so long as it is possible to drain liquid through the passages 19 and 20, or the passages 29 and 30.

I claim:

1. In a valve for controlling the flow of a hot fluid, the combination of a valve body having a seat, a valve head operably related to the seat to regulate the primary flow in one direction and including drain passages providing return communication through the head when engaging the seat, a valve plate controlling flow through the passages, and thermostatic means extending within the valve body and extendible in one direction when heated to shift the plate to closing position and retractible when cold to permit the plate to shift to open position.

2. In a valve for controlling the flow of a hot

fluid, the combination of a valve body having a seat, a valve head operably related to the seat to regulate the primary flow in one direction and including drain passages providing return communication through the head when engaging the seat, a valve plate controlling flow through the passages and gravity actuated to an open position, and thermostatic means extending within the valve body and extendible in one direction

5 when heated to shift the plate to closing position and retractible when cold to permit the plate to shift to open position.

6 3. In a valve for controlling the flow of a hot

15 fluid, the combination of a valve body having a seat, a valve head operably related to the seat, to regulate the primary flow in one direction and including drain passages providing return communication through the head when engaging the seat, a valve plate controlling flow through the 20 passages, thermostatic means extending within the valve body and extendible in one direction when heated to shift the plate to closing position, and means for shifting the plate to an open position when the thermostatic means retracts.

25 4. A self-draining valve for controlling the flow of a hot fluid comprising a casing having an inlet port, an outlet port and a valve seat between the ports, a valve head operably related to the seat for controlling primary flow from the inlet 30 to the outlet port, the valve head including drain passages providing return communication when the head engages the seat, a guide stem extending from the head within the inlet port, a valve plate on the inlet side of the head for controlling flow through the passages, and thermostatic means carried by the stem and extending within the inlet port, the means controlling a shifting of the plate to uncover the passages when the valve head closes and the temperature in the 35 inlet port falls below a predetermined value.

40 5. A self-draining, angle valve for controlling the flow of a hot fluid comprising a casing having an inlet port, an outlet port and a valve seat between the ports, the axes of the ports being substantially at right angles, a valve head operably related to the seat for controlling primary flow from the inlet to the outlet port, the valve head including drain passages providing return communication when the head engages the seat, and 45 thermostatically controlled valve means extending within the inlet port for regulating flow through the passages and adapted to uncover the 50 passages when the valve head closes and the temperature on the inlet side of the head falls below a predetermined value.
